UNITED STATES PATENT OFFICE

EDWARD C. HINCHLIFF, OF ROCKFORD, ILLINOIS, ASSIGNOR TO BURSON KNITTING COMPANY, OF ROCKFORD, ILLINOIS, A CORPORATION OF ILLINOIS

MULTIPLE SUTURE YARN CONTROL

Application filed April 25, 1930. Serial No. 447,145.

This invention relates to straight knitting machines, and is more particularly concerned with yarn controls, the same having to do with a multiple suture yarn control for use in knitting any desired fabric, but more particularly a split foot stocking having either a step toe or narrow high splice, or both.

In knitting a fabric with two different yarns, as for example, in the knitting of a split foot stocking where heavy sole yarn and light body yarn is used on opposite sides of a suture, it is a problem to keep the yarn that extends to the needles remote from the yarn transfer mechanism from becoming entangled during the knitting with a second yarn with the needles at the transfer or "home" end of the machine. This problem was solved by provision of a yarn retainer on one side of the bed behind which the first yarn could be deposited by a finger on the carrier of the second yarn, but the problem became more involved when it was desired to deposit this first yarn behind a retainer when the retainer had to be made in sections with gaps therebetween, one for each of the sutures, because in moving the first yarn from one suture point to another, the yarn would invariably catch in the one or more gaps of the previous sutures. It is, therefore, the object of this invention to provide practical ways and means of avoiding entanglement or catching of the first yarn as it is being deposited by the finger on the carrier of the second yarn at each commencement of the knitting with the second yarn, by guiding the first yarn over the suture gaps between contiguous yarn retainers.

More specifically stated, my invention contemplates the provision of special yarn sinkers or web holders in the gaps between the yarn retainers provided with upstanding projections preferably suitably rounded or arcuate on the top thereof and reaching from a point in front of the retainers to a point in the gaps between the retainers with the uppermost portion thereof preferably substantially in the same plane with the top of the retainers so that the yarn as it is being deposited back of the retainers by the finger on the carrier of the second yarn will be guided

over the top of said projections and cannot possibly get caught in the gaps between the retainers in the passage of the finger from the one retainer past a gap to the next retainer. My invention further contemplates the provision in the back of each of said projections of a suitable slot or recess for reception of the yarn to avoid its being chafed or cut off between the projections on the sinkers and the front of the sinker cap in the normal reciprocating action of the sinkers.

The invention is illustrated in the accompanying drawings, in which—

Figure 1 is a fragmentary plan view of a straight parallel row knitting machine embodying my invention;

Fig. 2 is a more or less diagrammatic view in perspective of the yarn control provided in accordance with my invention;

Fig. 3 is a fragmentary perspective view of a modified form of retainer, the use of which accomplishes the same purpose as the cooperating sinkers and yarn retainers of Fig. 2;

Fig. 4 is a fragmentary transverse vertical section taken on the line 4—4 of Figure 1 looking in the direction of the arrows;

Fig. 5 is a fragmentary transverse vertical section showing how each of the retainers is mounted on the sinker cap;

Figs. 6, 7 and 8 are diagrammatic views illustrating how the yarn control of my invention serves to retain the first yarn in an out of the way position during the knitting with the second yarn at each of the three sutures provided for in the machine illustrated in Figure 1, and

Fig. 9 is a side view of a split foot stocking having a step toe and narrow high splice, and produced on the machine of Figure 1.

The same reference numerals are applied to corresponding parts throughout the views.

Before proceeding with the description of the yarn control, attention is directed to Fig. 9 showing one example of knitting involving a multiplicity of sutures. There is a suture at 10 just behind the toe proper 11, as desired in a step toe, another suture 12 between the sole 13 and instep 14 and reaching to the heel 15, and still another suture 16 for the narrow high splice 17. The toe, sole, heel and high

splice are usually of a heavier and more durable yarn, which I will refer to hereinafter for the sake of convenience as the "first" yarn, whereas the instep and the rest of the body 5 of the stocking is usually of a lighter yarn, such as silk, to be hereinafter referred to as the "second" yarn. The first yarn is indicated at 18 in Figs. 6-8, and the second yarn is indicated in dotted lines at 19 in Fig. 6. In the 10 production of the stocking of Fig. 9, the toe 11 is started with a set-up in the usual way and knit by round and round knitting up to the beginning of the instep 14. Then, the instep and sole are knit by back and forth 15 knitting, the heel 15 being produced by narrowing and widening, and the back and forth knitting being continued to the top of the high splice, after which the leg is knit by round and round knitting to the top of the 20 stocking. At the step toe, which, of course, is at the commencement of the back and forth knitting with the two yarns, first one and then the other alternately, in a well known manner, the knitting with the second yarn 25 19 is limited to the needles spanned by the first retainer 20, as represented in Fig. 6, the gap 10' being for the first suture 10. The needles beyond the first suture gap 10' spanned in part by the next two retainers 21 and 22 30 at this stage of the knitting are knitting with the first yarn 18. Notice that, as indicated in dotted lines in Fig. 6, the second yarn 19 is used in knitting starting from the transfer end of the machine on one bed forward to 35 the suture point 10' and back on the same bed to the starting point, then across to the other bed and forward again to the suture point and back again to the transfer end of the machine and then out, and that during this back 40 and forth knitting, the first yarn 18 is held out of the way behind the retainer 20, as indicated in full lines. After completion of the step toe and upon commencement of the knitting of the sole 13 and instep 14 on opposite 45 sides of the suture 12, the pattern mechanism, in the case of knitting with the second yarn 19, throws into action an additional number of needles spanned by the second retainer 21, as indicated in Fig. 7, the knitting with the second yarn being carried past 50 the first suture point 10' up to a second suture point 12', the gap for which is shown between the second retainer 21 and a third retainer 22. During the knitting with the second 55 yarn, the first yarn is held out of the way behind the retainers 20 and 21, as shown in Fig. 7. After completion of the sole and heel, and upon commencement of the narrow high splice 17 defined by the suture 16, the 60 pattern mechanism throws into action in the knitting with the second yarn 19 still another additional number of needles spanned by the third retainer 22, as shown in Fig. 8, the knitting with the second yarn 19 being 65 carried past the suture points 10' and 12'

to the suture point 16'. During this knitting, the first yarn 18 is held out of the way behind all three retainers 20, 21 and 22. It will be observed in each of the three Figures 6, 7 and 8, that the knitting with the first yarn 70 is in each case started at the suture point and forward to the end of the bank of active needles of the one bed, then across the other bed and back to the suture point and forward again to the end of the bank of active needles and across to the first bed, then back to the suture point and out. In other words, the first yarn 18, at the end of each back and forth knitting operation therewith, is always extended from the same bed of needles from one 80 of the three suture points to the yarn carrier therefor on the transfer mechanism, that is, during the knitting of the foot and up to the top of the high splice 17. This first yarn, unless held out of the way, would obviously become entangled in the reciprocation of the carrier of the second yarn. There is no such possibility of interference, however, on the part of the second yarn during the knitting 85 with the first yarn, because the second yarn at the end of each back and forth knitting operation therewith extends from the transfer end of the bed directly to the carrier therefor on the transfer mechanism. From this much explanation, it is thought the purposes 90 and advantages of the yarn control of my invention will be easily understood from the following description when read in connection with the views showing the actual construction employed, especially if it be borne in mind that at the commencement of each knitting operation with the second yarn 19, the first yarn 18 must be deposited behind the one, two or three retainers, as the case may be, and that in this operation of depositing the yarn, it is imperative that there be no likelihood of its catching in either of, let us say the gaps 10' and 12', if, for example, the 95 yarn is to be deposited behind all three retainers. 100

Referring now more particularly to Figs. 1, 2 and 4, the numeral 23 is applied to the carrier of the second yarn 19 reciprocable lengthwise of the throat of the machine in ways 24 on sinker caps 25 extending longitudinally of the opposed beds of needles in the usual way. Beneath the sinker caps, each bed is made up of the usual needle supports 26 separated by division plates carried therewith on longitudinal supporting rods 27. The needles 28 are reciprocable in grooves in the tops of the needle supports in which they are held by the usual filler springs 29 provided under the sinker bed 30. The sinker cap 25 retains the sinkers or web holders 31 in place on the sinker bed. The sinkers 31 have the web holding hooks 32 on the front ends thereof. It is understood, of course, that the sinkers are arranged to be reciprocated in a 115 predetermined timed relation with the knit- 120

ting strokes of the needles so that the hooks 32 serve their usual web holding function.

In accordance with my invention, a plurality of retainers, equal in number to the number of sutures to be formed in the knitting, are provided in connection with the one bed of needles, behind which the first yarn is arranged to be deposited progressively, that is to say, behind one retainer in knitting on opposite sides of the first suture, behind two sutures in knitting on opposite sides of the second suture, and so on. In this case, as we have seen from the foregoing description, there are three sutures to be taken into account, namely, 10, 12 and 16, and for that reason, three retainers 20, 21 and 22 are provided, as shown in Figure 1. Each of the retainers 21 and 22 is preferably formed from a piece of small round stiff wire bent at each end in the form of a U 33, as shown in Figs. 2 and 5, the two ends 33 being bent in the same direction into parallelism with one another, as shown, and the ends 34 of the wires being bent at right angles each in the same plane with its U to constitute a means for supporting the retainers at opposite ends thereof. As shown in Fig. 5, the sinker cap 25 has holes 35 drilled therein from the front into which the ends 34 are driven or pressed. The retainer 20 is also made of a single piece of wire with the forward end shaped like the ends of the other retainers but having its other end suitably supported on an upwardly projecting portion of a small sheet metal bracket 36 suitably fastened to the transfer end of the sinker cap. The wire of the retainer 20 is extended beyond the bracket 36, as shown in Figure 1, far enough to always insure easy sliding of the yarn 18 over the same and behind the retainer 20 at the beginning of the operation of depositing the yarn behind the retainer or retainers. The depositing of the yarn is taken care of by means of a wire finger 37 bent generally into the shape of the numeral 4, as shown in Fig. 2, and suitably secured onto the yarn carrier 23 of the second yarn and projecting downwardly from said carrier, as indicated in Figure 1, at the proper location with reference to the one bed of needles to operate back and forth in the space between the retainers 20, 21 and 22 and the front of the sinker cap 25, as is thought to be clear in Figure 1. In Fig. 2 the finger 37 is shown behind the retainer 20 at an intermediate point of its stroke with the yarn carrier. This finger, in other words, passes through the U-ends 33 of the retainers over the shanks of the sinkers 31. This fact is indicated in Fig. 4 where the finger 37 appears in dotted lines. Now, between the end of the retainer 20 and the adjacent end of the retainer 21 there is a gap which has previously been designated by the numeral 10', and a similar gap at 12' between the end of the retainer 21 and the adjacent end of the retainer

22. Each of these gaps is necessitated for a suture needle. The suture needles are designated 28' to distinguish them from the other needles 28, they being all alike, and each of these suture needles has two sinkers provided on opposite sides thereof like the other needles, excepting that the sinker of each pair remote from the transfer end of the bed, designated by the numeral 31' so as to distinguish it from its companion sinker 31, has the top thereof specially formed to serve in the nature of a baffle or deflector for the yarn to keep it from dropping down into the gap when it is desired to have it slide over the same. It will be observed that the top of each of the sinkers 31' has a projection 38 reaching from a point in front of the retainers into the gap therebetween and having the top thereof rounded or arcuate so as to facilitate sliding of the yarn over the same and avoid likelihood of catching. The rear end of each of these projections 38 is approximately at the same elevation as the tops of the retainers (see Fig. 4) so that the yarn in sliding over the projection will naturally slide right onto the top of the next retainer and will not get caught between the projection and the end of the retainer. In Fig. 2 the yarn 18 is shown sliding over the top of the projection 38 at the first suture gap 10' preparatory to going onto the retainer 21. The rear end of each of the projections 38 is slotted, as indicated at 39, for reception of the yarn deposited behind the retainers. These slots are necessary, owing to the fact that the projections 38 reach to a point so close to the front of the sinker cap 25 that the yarn would be pinched or chafed between the rear end of the projections and the front of the sinker cap in the normal reciprocation of the sinkers, if no place were provided as a refuge for the yarn. That is, the baffle or deflecting action of the projections necessitates having them of a predetermined length, and there is not enough clearance between the rear ends of these projections and the front face of the sinker cap to allow for the full stroke of the sinkers and still leave enough clearance for the yarn, and the slots provide that clearance without in any way detracting from the successful functioning of the projections as guiding baffles or deflectors for the yarn. The slots 39 are, however, not made deeper than is actually necessary, so that there will be no chance of the yarn getting caught therein enough to interfere with its being easily removed when it becomes its turn to knit.

The operation of the yarn control is believed to be fairly clear from the foregoing description. After the completion of each back and forth knitting with the first yarn, and at the commencement of each knitting with the second yarn, the yarn carrier 23 for the second yarn in making its first forward stroke, is arranged to take care of the deposit-

ing of the first yarn behind the one or more retainers, by means of the finger 37 which reciprocates behind the retainers. Referring to Fig. 2, where the first yarn 18 is shown 5 extending from the second suture needle, this corresponding to the knitting illustrated in Fig. 7, it will be seen that the finger 37 on the forward stroke of the carrier deposits the yarn first behind the retainer 20 and then behind the retainer 21, the projection 38 on 10 the sinker 31' at the gap 10' serving to keep the yarn from getting caught. When the finger 37 is passing the gap 12', the yarn slips off, there being enough tension on the yarn 15 between the suture needle and the yarn carrier to begin with, and the tension being increased the closer the finger 37 comes to the point adjacent the gap of the suture needle, where the yarn extends from the suture needle to the finger approximately at right 20 angles to the plane of the retainers and the path of movement of the finger, to insure the slipping off of the yarn. The yarn is thus left in the position indicated in dotted lines 25 in Fig. 2 lying back of the retainers 20 and 21 and extending through the slot 39 in the projection 38 of the sinker 31' at the gap 10'. The yarn is, therefore, out of the way of the 30 finger on the return stroke of the carrier and the subsequent reciprocation of the carrier. After completion of the knitting with the second yarn and recommencement of the 35 knitting with the first yarn, when the yarn carrier for the first yarn is transferred into action, the first yarn is stripped off the retainers in the forward movement of the yarn carrier, and, of course, after completion of the 40 knitting operation with the first yarn, it is again deposited back of the retainer or retainers upon recommencement of the knitting with the second yarn.

As described, the fact that the sinkers 31' have the backs of the projections 38 slotted 45 as at 39 prevents any damage to the yarn in the normal reciprocation of the sinkers.

In Fig. 3 I have illustrated a modification wherein, instead of utilizing specially formed sinkers 31', I provide specially formed yarn 50 retainers such as that designated by the numeral 21', and use ordinary sinkers like those numbered 31. The special yarn retainers 21' are provided with projections 38' in the form of spurs reaching forwardly from the retainers at the end toward the transfer end 55 of the machine and bent laterally and downwardly preferably in a slight curve over the top of the sinker immediately alongside the end of the retainer. The spur projection 38' 60 may be provided by welding, soldering, or brazing a short piece of wire onto the wire retainer at the U-shaped end thereof. The operation of depositing the yarn in an out 65 of the way position with this form of combination yarn retainer and baffle or deflector is

practically the same as with the other form of my invention above described.

The foregoing description is believed to convey a clear understanding of my invention. The appended claims have been drawn 70 with a view to covering both forms illustrated, as well as other modifications such as will no doubt occur to those skilled in this art as a result of the disclosure.

I claim:

1. In a straight knitting machine, the combination with a bed of needles and a guide extending lengthwise of the throat of the machine and adapted to have yarn carriers reciprocate thereon lengthwise of the bed, of a plurality of yarn retainers disposed in an out of the way position with respect to the bed of needles in alignment with one another lengthwise of the bed and parallel with the guide, the said retainers being spaced from 80 one another at suture points, there being needles in the bed constituting suture needles at the suture points from which yarn is arranged to extend past one or more intervening retainers to the yarn carrier associated therewith when the latter is inactive, and means arranged in the reciprocation of a yarn carrier on the guide to thread the yarn extending from the suture needle onto the one or more yarn retainers between the said 85 suture needle and the yarn carrier associated therewith.

2. In a straight knitting machine, the combination with a bed of needles and a guide 90

extending lengthwise of the throat of the machine and adapted to have yarn carriers reciprocate thereon lengthwise of the bed, of a plurality of yarn retainers disposed in an out of the way position with respect to the bed of needles in alignment with one another lengthwise of the bed and parallel with the guide, the said retainers being spaced from 100 one another at suture points, there being needles in the bed constituting suture needles at the suture points from which yarn is arranged to extend past one or more intervening retainers to the yarn carrier associated therewith when the latter is inactive, means arranged in the reciprocation of a yarn carrier on the guide to thread the yarn extending from the suture needle onto the one or more yarn retainers between the said suture needle and the yarn carrier associated therewith, and means for guiding the yarn from 105 the end of one retainer onto the end of the next in the threading of the yarn onto the retainers.

3. In a straight knitting machine, the combination with a bed of needles and a guide extending lengthwise of the throat of the machine and adapted to have yarn carriers reciprocate thereon lengthwise of the bed, of a plurality of yarn retainers disposed in an out of the way position with respect to the bed 115 of needles in alignment with one another 120

125

lengthwise of the bed and parallel with the guide, the said retainers being spaced from one another at suture points, there being needles in the bed constituting suture needles at 5 the suture points from which yarn is arranged to extend past one or more intervening retainers to the yarn carrier associated therewith when the latter is inactive, means arranged in the reciprocation of a yarn carrier 10 on the guide to thread the yarn extending from the suture needle onto the one or more yarn retainers between the said suture needle and the yarn carrier associated therewith, and means in the spaces between the yarn 15 retainers at the suture points for guiding the yarn from one retainer to the next.

4. In a straight knitting machine, the combination with opposed beds of needles and a yarn carrier guide extending lengthwise of 20 the throat of the machine, of a plurality of yarn retainers provided in connection with one of the beds and extending from the transfer end of the machine in alignment with one another longitudinally of the bed and parallel with the yarn carrier guide, said retainers being spaced from one another at the suture points, there being suture needles in the bed at the suture points, the yarn at the end of each knitting operation with the needles 25 on the one side of a suture needle, remote from the transfer end of the machine, being arranged to extend from the said suture needle to the transfer end of the machine past one or more intervening yarn retainers, and means 30 arranged at the commencement of the knitting with the needles on the other side of the suture needle for depositing the said yarn onto the intervening yarn retainers so as to be out of the way during the knitting with said 35 needles.

5. In a straight knitting machine, the combination with opposed beds of needles and a yarn carrier guide extending lengthwise of 40 the throat of the machine, of a plurality of yarn retainers provided in connection with one of the beds and extending from the transfer end of the machine in alignment with one another longitudinally of the bed and parallel with the yarn carrier guide, said retainers being spaced from one another at the suture 45 points, there being suture needles in the bed at the suture points, the yarn at the end of each knitting operation with the needles on the one side of a suture needle, remote from the transfer end of the machine, being arranged to extend from the said suture needle to the transfer end of the machine past one or more intervening yarn retainers, and means operable 50 in the initial forward movement of the 55 yarn carrier associated with the needles on the other side of the suture needle for threading the yarn extending from said suture needle onto the intervening yarn retainers.

6. In a straight knitting machine, the combination with opposed beds of needles and a

yarn carrier guide extending lengthwise of the throat of the machine, of a plurality of yarn retainers provided in connection with one of the beds and extending from the transfer end of the machine in alignment with one another longitudinally of the bed and parallel with the yarn carrier guide, said retainers being spaced from one another at the suture points, there being suture needles in the bed at the suture points, the yarn at the end of each knitting operation with the needles on the one side of a suture needle, remote from the transfer end of the machine, being arranged to extend from the said suture needle to the transfer end of the machine past one or more intervening yarn retainers, means operable 70 in the initial forward movement of the 75 yarn carrier associated with the needles on the other side of the suture needle for threading the yarn extending from said suture needle onto the intervening yarn retainers, and means at each of the suture points for guiding the yarn from the end of one retainer onto the next to avoid catching of the yarn at the suture points in the threading of the yarn 80 onto more than one retainer.

7. In a straight knitting machine, the combination with a bed of needles, sinkers cooperating therewith and a sinker cap for the latter, of a plurality of yarn retainers disposed in spaced end to end relation lengthwise of the bed spanning the shanks of the sinkers and carried on the sinker cap in spaced parallel relation to the latter, there being suture needles in the bed for the different suture points in the spaces between the retainers, and means operable lengthwise of the bed between the retainers and the sinker cap for threading yarn extending from any one of the suture needles onto said retainers. 95

8. In a straight knitting machine, the combination with a bed of needles, sinkers cooperating therewith, and a sinker cap for the latter, of a plurality of yarn retainers disposed in spaced end to end relation lengthwise of the bed spanning the shanks of the sinkers and carried on the sinker cap in spaced parallel relation to the latter, there being suture needles in the bed for the different suture points in the spaces between the retainers, and at least one sinker alongside each suture needle in each of said spaces, means operable lengthwise of the bed between the retainers and the sinker cap for threading yarn extending from any one of the suture needles onto said retainers, and means on each of the sinkers at the suture points for guiding the yarn from the one retainer to the next. 100

9. In a straight knitting machine, the combination with a bed of needles, sinkers cooperating therewith, and a sinker cap for the latter, of a plurality of yarn retainers disposed in spaced end to end relation lengthwise of the bed spanning the shanks of the sinkers and carried on the sinker cap in spaced parallel 115

relation to the latter, there being suture needles in the bed for the different suture points in the spaces between the retainers, and at least one sinker alongside each suture needle in each of said spaces, means operable lengthwise of the bed between the retainers and the sinker cap for threading yarn extending from any one of the suture needles onto said retainers, and means on each of the 10 sinkers at the suture points for guiding the yarn from the one retainer to the next, said means comprising a projection on each of said sinkers extending on an incline from a point in front of the yarn retainers rearwardly at least up to said retainers and to approximately the same elevation as said retainers for the purpose described.

10. In a straight knitting machine, the combination with a bed of needles, sinkers cooperating therewith, and a sinker cap for the latter, of a plurality of yarn retainers disposed in spaced end to end relation lengthwise of the bed spanning the shanks of the sinkers and carried on the sinker cap in spaced parallel relation to the latter, there being suture needles in the bed for the different suture points in the spaces between the retainers, and at least one sinker alongside each suture needle in each of said spaces, means operable 20 lengthwise of the bed between the retainers and the sinker cap for threading yarn extending from any one of the suture needles onto said retainers, and means on each of the sinkers at the suture points for guiding the yarn 25 from the one retainer to the next, said means comprising a projection on each of said sinkers extending on an incline from a point in front of the yarn retainers rearwardly at least up to said retainers and to approximately 30 the same elevation as said retainers for the purpose described, there being a shoulder on said sinkers behind said projections and the yarn being arranged to be deposited behind said shoulder in front of the sinker 35 cap, the shoulder on each of said sinkers being provided with a recess to accommodate the yarn therein and prevent pinching thereof between the shoulder and the sinker cap.

11. The method of controlling one of two 40 yarns to avoid entanglement during the knitting with the other yarn in a straight knitting machine, where the two yarns are used in knitting on opposite sides of several sutures, the method consisting in providing 45 as many yarn retainers as there are sutures, placing the retainers so that they terminate at the suture points, and, in knitting with the second yarn up to any given suture point, depositing the loose portion of the first yarn behind the retainer or retainers associated with the previous suture or sutures.

12. The method of controlling one of two 50 yarns to avoid entanglement during the knitting with the other yarn in a straight 55 knitting machine, where the two yarns are

used in knitting on opposite sides of several sutures, the method consisting in providing as many yarn retainers as there are sutures, placing the retainers so that they terminate at the suture points, and, in knitting with the second yarn up to any intermediate suture point or up to the farthest suture point, threading the loose portion of the first yarn onto the retainers in the first forward stroke of the carrier of the second yarn, and guiding the same from retainer to retainer in the movement of the yarn past the suture points to avoid catching on the retainers at any one of said points.

In witness of the foregoing I affix my signature.

EDWARD C. HINCHLIFF.
